UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

SHIFT-KEY MECHANISM.

SPECIFICATION forming part of Letters Patent No. 766,299, dated August 2, 1904.

Original application filed July 5, 1902, Serial No. 114,362. Divided and this application filed June 12, 1903. Serial No. 161,183. (No model.)

To all whom it may concern:

Be it known that I, FRANZ X. WAGNER, a citizen of the United States, and a resident of the borough of Bronx, city, county, and State of New York, have invented certain new and useful Improvements in Shift-Key Mechanism, of which the following is a specification.

My invention relates to shift-key mechanisms for type-writers, and has for its object to provide a means for locking the platen in the upper position.

The invention also consists in certain features of construction and combination of parts, as will be fully described hereinafter and specifically pointed out in the claims.

I desire it to be understood that while I have shown what I consider at present the best manner of carrying my invention into effect various modifications may be made in the arrangement and construction of the several parts without departing from the nature of my invention.

The present application is a division of one filed by me in the United States Patent Office on July 5, 1902, Serial No. 114,362.

Reference is to be had to the accompanying drawings, in which—

Figure 1 is a sectional elevation of a type-writing machine provided with my improvement. Fig. 2 is a detail view from the other side of the mechanism for preventing the jarring or trembling of the carriage and to lock it in either the upper or lower positions; and Fig. 3 is a sectional elevation similar to Fig. 1, but looking from the opposite direction, and showing the various parts in a different position.

On each side of the machine is a bell-crank lever 5, fulcrumed at 6 and provided with a pin 7, adapted to be engaged by a shift-key lever 8, also fulcrumed at 6. The shift-key is indicated at 9. By depressing either of the shift-keys the bell-crank lever will move forward and the rollers 10 will be raised so as to bring the front section of the carriage into the upper position. For the purpose of locking the carriage in the upper position one of the shift-keys is provided with a projection

11, adapted to move in an L-shaped slot of a locking-lever 12, fulcrumed at 12^a. This lever is provided with a handle 12^b and has a tendency to lean forward in the position illustrated by Fig. 1. If the shift-key 9 is depressed, the locking-lever will fall forward upon the projection 11 reaching the enlarged lower end of the slot, and thus the carriage will be locked in its upper position until the lever 12 is thrown back by hand. When this locking action is not desired, the lever 12 is thrown back entirely, so that the projection 11 will move in front of it.

To prevent the locking-lever 12 from being thrown back fully except when the shift-key 9 is in its upper position, Fig. 1, the locking-lever 12 is provided with a tongue 12^c, which engages the projection 11 on the shift-key as the latter is depressed. Thus the locking-lever will always be in proper position for automatically locking the shift-key unless the said locking-lever has been thrown back before the shift-key is depressed. The length of the tongue 12^c is such that when the shift-key is in its normal position the projection 11 is above the end of said tongue, and the locking-lever can therefore be thrown back, as explained above, if desired.

To prevent the carriage from jarring or trembling and to hold it firmly in either the upper or lower position, the shift-keys are connected under slight lost motion with mechanism whereby the carriage-support or lifting-frame 13 is securely held in either of its two positions. For this purpose I provide a lever 14, fulcrumed at 15 and under the influence of a spring 16. This lever has an oblique slot 14^a, which is engaged by a pin 17 upon one of the bell-crank levers 5, so that upon the forward movement of this bell-crank lever the lever 14 will be swung downward against the tension of the spring 16, as best shown in Fig. 3. The lever 14 has two members, one of which, 18, is arranged to engage the carriage-support or the lifting-frame 13 when the latter is in its lower position, as best shown in Fig. 2, while the other member, 19, is located at the top and is adapted to form a

support for a pin 20 upon the frame 13 when the latter is in its upper position, as in Fig. 3. It will be understood that the carriage or the platen portion thereof is thus held firmly 5 in the upper or lower position against accidental movement without, however, interfering with the operation of the shifting-keys.

What I claim as new, and desire to secure by Letters Patent, is—

- 10 1. In a type-writer or like machine, the combination with a carriage having a platen-section capable of being shifted into different positions, of means for shifting the platen-section, and a movable steadyng device mounted directly on the frame of the machine for holding or bracing the platen-section against accidental movement relatively to the frame in either position.
- 15 2. In a type-writer or like machine, the combination with a carriage having a platen portion capable of being shifted into different positions, of means for shifting the platen-section, and a spring-pressed steadyng device mounted directly on the frame of the machine for holding or bracing the platen-section against accidental movement relatively to the frame in either position.
- 20 3. In a type-writer or like machine, the combination with a carriage having a platen-section capable of being shifted into different printing positions, of means for shifting the platen-section, a steadyng device movably mounted on the frame of the machine for holding or bracing the platen-section against accidental movement in either of its printing positions, said steadyng device being provided with a slot, an operating device for said shifting means, and a pin on said operating device projecting into the slot of said steadyng device for throwing said steadyng device out of action, so as to allow the platen-section to pass from one printing position to another.
- 25 4. In a type-writing machine or the like, the combination with a carriage having a platen-section adapted to be shifted into different printing positions, of means for shifting the

50 platen-section, a steadyng device for holding or bracing the platen-section against accidental movement in either of its printing positions, and an operating device for said shifting means, which operating device is provided with means for throwing the steadyng device out of action, so as to allow the platen-section to pass from one printing position to another.

55 5. In a type-writer or like machine, the combination with a carriage and a shift-key for moving the platen portion of the carriage into an upper or lower position, of a locking-lever movably mounted on the frame and adapted to be shifted into or out of the path of a co-operating locking portion of the shift-key, to either allow the shift-key to return to its original position or to automatically lock the said shift-key in its lower position, said locking-lever being provided with means for preventing it from being thrown out of co-operative relation to said locking portion of the shift-key unless said key is in its upper position.

60 6. In a type-writer or like machine, the combination with a carriage and a shift-key for moving the platen portion of the carriage into an upper or lower position, of a locking-lever movably mounted on the frame and adapted to be shifted into or out of the path of a co-operating locking portion of the shift-key, to either allow the shift-key to return to its original position or to automatically lock the said shift-key in its lower position, said locking-lever being provided with a tongue extending in advance of the path of said locking portion of the shift-key, but terminating below the said portion when the shift-key is in its upper position.

65 In testimony whereof I have signed my name to this specification in the presence of two subscribing witnesses.

70 FRANZ X. WAGNER.
